UNITED STATES PATENT OFFICE

ARGYLE CAMPBELL, OF CHICAGO, ILLINOIS, ASSIGNOR TO ENTERPRISE RAILWAY EQUIPMENT COMPANY, OF CHICAGO, ILLINOIS, A CORPORATION OF ILLINOIS

LOAD-DISCHARGING CAR

Application filed March 8, 1928. Serial No. 259,940.

This invention relates to improvements in load discharging cars and more especially to the discharge doors and the door operating mechanism for same.

An object of my invention is to provide a simple door operating mechanism wherein is employed a bodily movable shaft adapted to be moved to a supporting position beneath the car doors when the latter are in closed position, and to provide supporting means for the shaft whereby movement of the same may be effected with comparative ease, friction reduced to a minimum and the doors safely and securely locked in the closed position.

It is also an object of my invention to provide a door operating mechanism having a bodily movable door operating shaft adapted to normally gravitate to a supporting position beneath the door as the door approaches the closed position, and to provide means for displacing the shaft out of the path of movement of the door and maintaining the said shaft away from the free edge of the door when the door is in alignment with the shaft.

A still further object of my invention is to provide a dumping door having a series of stiffening corrugations embossed therein and to further provide suitable bracing brackets whereby the stiffening effect of said corrugations and a continuous beam effect maintained between the corrugations and the door operating mechanism.

Other and further objects of the invention will more clearly and fully appear from the description and claims hereinafter following.

In the drawings forming a part of this specification, Figure 1 shows a plan view of a portion of a car having my improved construction embodied therein. Figure 2 is a transverse vertical sectional view of a portion of the car and corresponds substantially to the line 2-2 of Figure 1. Figure 3 is a longitudinal vertical sectional elevational view of that portion of the car showing the doors and door operating mechanism, said view being taken on a line corresponding substantially to line 3-3 of Figure 1. Figure

4 is a view similar to Figure 2 except that the shaft is displaced from its supporting position beneath the door and the latter is shown in a partially opened position. Figure 5 is a view similar to Figure 4 except that the door is shown in a slightly different position and with a somewhat greater opening. Figure 6 is a fragmentary vertical elevational view of one of the cross beams illustrating one of the swinging hanger supports. Figure 7 is a longitudinal vertical elevational view of a portion of the car showing the door operating shaft actuating and locking mechanism. Figure 8 is an end elevational view of the shaft locking mechanism, said view representing a section through the shaft as taken on a line corresponding substantially to a line 8-8 of Figure 7. Figure 9 is an end elevational view of the construction shown in Figure 7.

As shown in the drawings, A indicates the centersill of the car, B crossbeams of the car, C one of the side walls, D dumping doors, E a door operating shaft, F shaft supporting link hangers, G door winding connections, H the shaft locking mechanism, and J the shaft actuating mechanism. The car as shown is of the type commonly referred to as a general service car which usually includes a series of dumping doors hinged adjacent the longitudinal center of the car and adapted to discharge to the sides of the track. Inasmuch as the construction of the car on both sides of the longitudinal center of the car and the construction of each door and the associated door mechanism is similar for the various doors, the description hereinafter following is confined to so much of the car as necessary to illustrate the application of the mechanism to one door.

The centersill A is of the box girder form and includes webs 10, bottom chord 11, top chords 12, top cover plate 13, and secured to said sills at intervals lengthwise of the car are door supporting hinge butts 14.

The crossbeams B each include a pan-shaped diaphragm 15, bottom tie plate 16, top cover plate 17, and connecting angles 18 and 19. The side walls C of the car include a lower chord member 20 of angular formation,

side sheet 21, and side stakes 22, the latter being disposed at each crossbeam and secured directly thereto.

Each dumping door D is preferably formed of a metallic plate of a pan-shape formation with its front, rear and side marginal edges formed with depending flanges as indicated at 23, 24 and 25 respectively. The body of the plate is strengthened by a series of embossed corrugations 26 which extend substantially at right angles to the free or swinging edge of the door, said corrugations being separated by intervening valleys 27. The corrugations are formed with tapered ends there-by providing for corrugations of decreased width and height adjacent their ends, thus presenting valleys of increased width adjacent the tapered portions of the corrugations. The corrugations do not extend to the extreme edge of the door in order that the door may present a section of flat plate adjacent the free edge of the door as indicated at 127 for the purpose of abutting the horizontal flange of the lower chord 20 of the car side C.

As will be understood, there will be preferably one door D between each pair of the cross members B of the underframe on each side of the centersill. In carrying out my invention the diaphragms 15 are slotted at their outer ends so as to accommodate the longitudinally extending shaft E of the door operating and supporting mechanism E. The shaft E is rotatably mounted in perforations 28 formed in the swinging link hangers F which are each mounted on pivot 29 carried on bracket 30, the latter in turn being securely riveted to the vertical web of the crossbeam diaphragms 15. Each bracket 30 is provided with a slot 31 of arcuate form and includes a plurality of walls as indicated at 32 and 33, said walls being separated by an intervening space between which the associated hanger F is mounted. The said walls 32 and 33 provide a stable support for the pivot 29. The link supporting pivot 29 is preferably mounted beyond the free edge of the door and beneath the horizontal flanges of the lower chord 20 of the side wall C, said pivot 29 being so arranged as to permit the hangers to gravitate to a vertical position with the shaft E directly beneath the said pivot 29 as indicated in Figures 2 and 6, whereby a straight line extending through the pivot 29 and passing through the axis of the shaft will lie on a substantially vertical line as indicated at 34 in Figure 6.

Co-operating with the door D to raise the same and bring it to a closed position are the flexible connections G each having one end attached to the shaft and the opposite end to the door. There are preferably two of these connections G to each door but inasmuch as the construction is the same in each instance the description will be confined to one of said connections. The attachment of

the connection to the door is effected through the medium of a bracket casting 35 which is secured to the underside of the door and to a beam member 36 secured to the door, the latter extending transversely across the plane of the corrugations 26. The said beam member 36 is preferably of a shape to include a flange 37 lying against the door plate and a web 38 extending normal to the plane of the door. The bracket 35 is extended outwardly beyond the outer flange 23 of the door, the latter being cut away as indicated at 39—39 to accommodate the passage of said bracket across the plane of the door flange. Inwardly of the said door flange the bracket is formed with lateral walls 40—40 which extend outwardly from the respective sides of the bracket and are riveted as at 41 to the door flange on each side of the cut away portion thereby providing continuity of reinforcement of the flange 23 across the plane of the bracket 35, and a continuous door beam effect is thereby maintained from the hinged edge of the door to its forward extremity. Outwardly of the flange 23 the bracket is provided with a plurality of arms 42—42 spaced from each other and formed with a flat bearing portion on their under side as indicated at 43 for a purpose hereinafter described, each of said arms 43 being braced laterally against the adjacent wall 40 by a lateral integral wall portion 44 which extends beneath the flange 23 of the door. The projecting arms 42 are perforated to receive the pivot 45 whereby connection is effected between the door and the flexible connection G. Each bracket 35 is preferably disposed centrally of one of the corrugations and riveted through the upper flange 37 of the beam member 36, and to the door plate on each side of and in the plane of said corrugation by rivets 46, and also secured centrally of the corrugation to the vertical web 38 of the said beam member 36 by means of rivet 47. In this manner the bracket casting 35 continues the stiffening effect of the corrugations beyond the termination of said corrugation and outwardly to the door operating mechanism and also co-ordinates the strength of a plurality of corrugations due to the effective manner in which the bracket is secured to the beam member 36, and the fact that the said beam is extended across the plane of a plurality of corrugations, and secured to the door intermediate said corrugations throughout the length of the door by means of rivets 46.

The connection G is formed of a plurality of links movably united by means of rivets and includes an end link 48 pivotally united with link 49 which in turn is pivotally connected with link 50, the latter being pivoted to link 51 which in turn is pivoted to hub 52, the latter being rigidly united with the operating shaft E by means of bolts 53, the end link 48 being adapted to lie between the spaced

arms 42 of the bracket 35, and pivotally united thereto by means of pivot pin 45. The link 48 is formed on its under side with a flat seating portion 54 adapted to align with seats 43 on the arms 42 of bracket 35, when the door is in closed position, said seats 43 and 54 being adapted when the doors are in closed position to rest on a flat seat 55 formed on the hub member 52. The link 48 is provided on each side thereof with lugs 56 adapted to co-operate with upstanding lugs 57 on the hub castings 52 whereby said link and hub castings are locked relatively to each other with the effect of a unitary structure when the links are fully wound around the hub castings.

The relation of pivot 45 on the door is so disposed that when the door is in closed position and the shaft beneath the door in the fully closed position as indicated in Figure 2, the center of the pivot 45 will lie substantially above the axis of the shaft or preferably slightly to the far side and beyond vertical line 34 extending through the central axis of the shaft, thereby relieving the shaft of all torsional effect and providing a self-locking mechanism.

Each shaft E is preferably actuated from the end of the car by means of an actuating mechanism J, which includes a ratchet wheel 58 fixedly mounted on the shaft E and a rotatably mounted operating member, including an inner wall 59 and an outer wall 60, said walls being united by rivets 61 and spaced from each other by thimbles 62. On the outer wall 60 there is formed an integral socket 63 adapted to receive a removable operating bar. Mounted on one of the thimbles 62 is a pivoted pawl 163 adapted to engage with the teeth of ratchet 58 for rotation of the shaft in either direction.

The shaft locking means H is adapted to lock the shaft during the winding operation and includes a ratchet wheel 64 fixedly mounted upon the shaft, a supporting member 65 pivotally mounted with respect to the shaft and maintained against turning movement by a slotted connection with bracket 66, said bracket being provided with a fixed lug 67, on which the member 65 swings. A locking pawl 68 is pivotally mounted on the member 65, said pawl being adapted to engage with the teeth of the ratchet wheel 64 to lock the shaft against movement in an unwinding direction. Co-operating with said pawl 68 to lock the same in engagement with the ratchet wheel is the locking cam 69.

Assuming the doors to be in open position as indicated by dotted lines in Figure 2, the operation of the device is as follows: the shaft E is rotated in a counter-clockwise direction, assuming the parts positioned as in Figs. 2, 4, 5 and 9, by means of the door actuating mechanism H. As this rotation progresses the flexible connection will wind

around the hub casting 52, the shaft lying in the path of the door in the lower portion of the slot during the initial movement, and until such time as the door approaches the shaft when the links of the connection will 70 assume a position between the hub and the free edge of the door, which on continued rotary movement of the shaft will raise the door and force the shaft outward in the slot 75 as indicated in Figure 5. Continued rotation of the shaft in the indicated direction will bring the parts to the position as indicated in Figure 4, when the lugs 56 and 57 formed on the link and lug respectively will 80 engage and thereafter said link 48 and hub 52 will move as a unitary structure, the link and hub providing the effect of a rigid arm connection between the shaft and the door of a length indicated at 70. From the position indicated in Figure 4, further revolution of 85 the shaft through an arc of approximately ninety degrees will swing the link member E beneath the door and bring the door to a closed position. With the parts as indicated in Figure 4 it will be noted that final locking 90 action is in nature of the closing action of a toggle joint, the line 34 in the inclined position indicating the fixed points or base and arms 70 and 71 indicating the three pivots of the toggle, these being the axis of the shaft 95 E, and pivots 29 and 45. By reason of this toggle action very greatly increased mechanical advantage is obtained at the close of the door operation, said increase in leverage being also available to move the shaft away 100 from its supporting position beneath the door, it being understood that the releasing of the doors is a reversal of the closing operation.

I have herein shown and described what I now consider the preferred manner of carrying out my invention, but the same is merely illustrative and I contemplate all the changes and modifications that come within the scope of the claims appended hereto.

What I claim is:

1. In a railway car, the combination with a car door; of a swinging operating shaft; a connection from the shaft to the door, said connection including: an end link pivotally attached to the door; and interengaging lugs between said end link and the shaft arranged to force the shaft away from the edge of the door when the shaft is rotated in an unwinding direction.

2. In a railway car, the combination with a drop door; of a pivoted swinging shaft mounted adjacent the free edge of the door and adapted to move to a supporting position beneath the door; a flexible connection 115 interposed between said shaft and said door; said connection including an end link pivotally attached to a rigid part of the door, said end link when the shaft is in supporting position beneath the door being adapted to lie 120

120

125

130

between the door and the shaft; and inter-engaging means between said end link and the shaft to provide relative displacement of the parts on the initial rotation of the shaft in an unwinding direction.

3. In a railway car, the combination with the car framing; of a dumping door carried by the framing; vertically swinging links pivotally mounted on the car framing adjacent the free edge of the door; a door operating shaft rotatably mounted in said swinging members; and a flexible connection connecting said shaft and door, said connection consisting of a plurality of movably united elements interposed between said shaft and said edge of door, said shaft and one of the elements of the connection having co-operating means to force the shaft away from said edge of the door when the shaft is rotated in an unwinding direction.

4. In a railway car, the combination with a hinged door; of a rotatably mounted shaft; pivotally mounted means for supporting the shaft, said supporting means being so mounted as to adapt the shaft to have a bodily movement in the path of movement of the door and to assume a position beneath the door when the latter is in closed position; and a connection from the shaft to the door, said connection including a plurality of movably united elements of appreciable width and depth whereby as the shaft is rotated in a direction to close the door said elements will assume a position between the shaft and free edge of the door and maintain the shaft outwardly of the door.

5. In a railway car, the combination with the cross members of the car; of a dumping door mounted between said cross members; swinging hangers pivoted to the cross beams adjacent their outer ends; a winding shaft mounted in said hangers; and flexible connections connecting said shaft and door, said connections including a plurality of movably united elements interposed between the shaft and the edge of the door, said flexible connections and the shaft having cooperating means arranged to effect outward movement of the shaft away from the free edge of the door when the shaft is rotated in an unwinding direction.

6. In a railway car, the combination with a car framing including vertically disposed members and a drop door mounted between said members; of a rotatably mounted shaft mounted in said members adjacent the free edge of the door; means for supporting the shaft in position, said supporting means including swinging hangers pivotally mounted upon brackets secured to said vertically disposed members, said brackets including spaced walls between which said hangers are mounted; and a slot within which the said shaft is adapted to have arcuate movement,

said slots having stops at each end to limit the travel of said shaft.

7. In a railway car, the combination with the car framing; of a dumping door; a bodily movable and rotatable door supporting shaft mounted adjacent the free edge of the door and adapted to assume a position beneath the door when the latter is in closed position; bearings within which the shaft is rotatably mounted, said bearings being pivotally mounted on the car framing above the shaft; a connection from the shaft to the door, said connection including a drum fixed relatively to the shaft, said drum being of polygonal form and presenting a plurality of faces; links adapted to wind around the faces of the drum, said links being pivotally united to each other and corresponding in number to the number of faces of the drum; a bracket carried by the door, said bracket having the terminal link of the connection pivoted thereto, the center of said pivot when the door is in closed position being disposed above the axis of the shaft.

8. In a railway car, the combination with the car framing; of a dumping door carried by the frame; bearings pivotally mounted adjacent the free edge of the door; a rotatable door supporting shaft mounted in said bearings and adapted to assume a position beneath the door when the latter is in closed position; a bracket extending outwardly beyond the free edge of the door; a connection from the shaft to the door, said connection including a polygonal shaped hub formed with a plurality of faces; links adapted to wind around the hub, said links being pivotally united and corresponding in number to the number of faces on the hub, the end link of said connection being pivoted to the bracket on the door and adapted to lie between the door and the shaft when the latter is in supporting position beneath the door; and inter-engaging lugs between one of the links and the hub for locking the links relative to the hub.

9. In a railway car, the combination with a dumping door; of a shaft mounted in swinging hangers adjacent the free edge of the door, said shaft being so mounted as to permit the shaft to normally lie in the path of movement of the door; and a connection extending between the shaft and the door, said connection including an end link pivotally mounted on the door, said point of connection between the door and end link being adapted to lie above the axis of the shaft when the door is in closed position; and inter-engaging lugs between said end link and shaft for forcing the shaft away from the edge of the door when the shaft is rotated in an unwinding direction.

10. In a railway car, the combination with a dumping door and an operating mechanism for said door; the said operating mech-

- anism including: a rotatable shaft; swing-
ing links in which the shaft is rotatably
mounted; and a connection from the shaft
to the door, said connection including end
links pivotally attached to the doors, said
pivotal connection between the end link and
the door when the door is in closed position
being adapted to lie slightly to one side and
beyond a straight line joining the pivot of
the swinging link and the axis of the shaft
whereby the mechanism will be rendered
self-locking; and co-operating shoulders on
said terminal link and the shaft, so arranged
as to force the shaft away from the edge of
the door when the shaft is rotated in an un-
winding direction.

11. In a railway car, the combination with a drop door; of a pivoted swinging shaft mounted adjacent the free edge of the door; said shaft being pivotable between said

- 20 a flexible connection interposed between said shaft and said edge of door, said connection including an end link pivotally attached to a rigid part of the door, said pivotal point of attachment of the link being disposed above the axis of rotation of the shaft so that when the door is in closed position the shaft is locked against rotation in an unwinding direction; and co-operating means on said link and shaft arranged to force the

25 shaft away from the edge of the door when the shaft is rotated in an unwinding direction.

12. In a railway car, the combination with a dumping door; of a door supporting shaft

- 35 a latching device, and a connection extending between the shaft and the door, said connection including an end link pivotally attached to a rigid part of the door, said
40 pivotal point of attachment of the link being disposed above the axis of rotation of the shaft so that when the door is in closed position the weight of the door will lock the shaft against rotation in an unwinding direction.

45 rection.

13. In a railway car, the combination with
a dumping door; of an operating mechanism
for said door, the said operating mechanism
including: a rotatable shaft; swinging links
50 in which the shaft is rotatably mounted;
and a connection from the shaft to the door,
said connection including an end link pivot-
ally mounted with respect to the door, the
pivot between the connection and the door be-
55 ing so disposed as to lie when the door is in
closed position slightly to one side and be-
yond a straight line joining the pivot of the
swinging link and the axis of the shaft
whereby the closing action of the mecha-
60 nism will be the closing action of a toggle
joint connection.

14. In a railway car, the combination with a hinged door; of an operating shaft and means for swingingly supporting said shaft for movement into and out of support-
65

ing position with reference to said door; and means connecting said shaft and door and operable to swing said shaft into supporting position and provide a toggle action for locking said door when the same is closed. 70

15. In a railway car, the combination with a hinged door; of a rotatable operating shaft and means for swingingly supporting said shaft for movement into and out of supporting position with reference to said door; and connections between said shaft and door, including elements arranged to provide a toggle action with reference to said shaft and door to effect movement thereof when said shaft is rotated. . . .

16. In a railway car, the combination with a hinged door; of a rotatable operating shaft; hangers for swingingly supporting said shaft; and connections from said shaft to said door, said connections including a rigid element for moving said shaft out of the path of movement of said door. 85

17. In a railway car, the combination with
a hinged door; of an operating shaft adapt-
ed to be moved into and out of supporting
relation with reference to said door; hanger
means for swingingly supporting said shaft
for its operative movements; a connection
between said shaft and door including a
rigid element operable to assume a position
between the shaft and door to move the shaft
out of its normal position. 90 95

In witness that I claim the foregoing I have hereunto subscribed my name this 24th day of February, 1928.

ARGYLE CAMPBELL.
